UNITED STATES PATENT OFFICE.

JOHNSON H. NEEDLES, OF ATLANTIC, IOWA.

SHOVELING-BOARD FOR WAGONS.

SPECIFICATION forming part of Letters Patent No. 403,953, dated May 28, 1889.

Application filed January 18, 1889, Serial No. 296,776. (No model.)

To all whom it may concern:

Be it known that I, JOHNSON H. NEEDLES, a citizen of the United States, residing at the city of Atlantic, in the county of Cass and 5 State of Iowa, have invented a new and useful Shoveling-Board or End-Gate for Wagons, of which the following is a specification.

The objects of my improvements are to provide a cheap, convenient, and durable shoveling-board. I attain these objects by the invention illustrated in the accompanying drawings, in which—

Figure 1 is a perspective view of the shoveling-board detached from the wagon-box. Fig. 15 2 is a perspective view of the shoveling-board attached to the wagon-box, showing the shoveling-board closed. Fig. 3 is a perspective view of the shoveling-board attached to the wagon-box, showing the board let down or 20 opened. Fig. 4 is a detailed perspective view of the catch.

Similar letters refer to similar parts throughout the several views.

The shoveling-board A is composed of the 25 bottom i and the sides k k. The sides are firmly secured to the bottom i. The strap-bolts w w are secured to the sides of the shoveling-board, and their lower ends extend through the bottom i. Their upper ends project beyond the sides of the shoveling-board and are bent, forming hooks. The lugs or staples b are firmly secured, one to each side of the wagon-box. The supports d d are pivoted at their lower ends to the sides of the 35 shoveling-board and at their upper ends to the sides of the wagon-box. The blocks a are firmly secured to the sides of the wagon-box, there being two blocks, one upon each side of the wagon-box. The catch e is bolted or firmly 40 secured to the under side of the block a, there being two catches, one secured to each block. The cross-bars t t t are secured to the bottom i of the shoveling-board.

The supports C C are each composed of the 45 iron straps or bars m and n. The straps m and n are pivoted together near their ends, forming a joint. The straps m m of the sup-

ports C C are pivoted to the sides of the shoveling-board, and the straps n n are pivoted to the blocks a. The strap m is made 50 longer than the strap n, and the straps m and n are made of suitable length, so that when the supports C C are folded and held by the catch e, as shown in Fig. 2, the shoveling-board will be held in a proper position by the 55 folded supports C C to close the rear end of the wagon-box.

When the shoveling-board is closed, as shown in Fig. 2, the hooked ends of the strap-bolts w w engage with the lugs b, thus more 60 securely closing the end of the wagon-box.

When the shoveling-board is open or let down, as shown in Fig. 3, it is supported by the supports d d and the supports C C.

The shoveling-board can be closed and 65 locked by folding the jointed supports C C and engaging them with catches e, as shown in Fig. 2.

The shoveling-board can be readily opened or let down by lifting the supports C C out of 70 the catches e and unfolding them.

Having described my invention, what I claim as new, and desire to secure by Letters Patent, is—

1. The shoveling-board A, the jointed supports C, pivoted at one end to the outside of the sides of the shoveling-board and at the other end to the block a, the support d, pivotally connected to the shoveling-board and wagon-box, the wagon-box, and the block a, 75 firmly secured to the wagon-box and being provided with the catch e, all combined and arranged substantially as described.

2. The shoveling-board having pivoted to it the supports C and d, and having secured 85 to it the hooked strap-bolt w, in combination with the wagon-box having secured to it the lug b, and block a, provided with the catch e, substantially as set forth.

JOHNSON H. NEEDLES.
